UNITED STATES PATENT OFFICE.

NATHANIEL H. MERRIAM AND EDMUND H. SAWYER, OF LEXINGTON,
MASSACHUSETTS.

BOBBIN TAKE-UP FOR LOOMS.

SPECIFICATION forming part of Letters Patent No. 747,307, dated December 15, 1903.

Application filed October 6, 1902. Serial No. 126,049. (No model.)

To all whom it may concern:

Be it known that we, NATHANIEL H. MERRIAM and EDMUND H. SAWYER, both residing at Lexington, in the county of Middlesex, 5 Commonwealth of Massachusetts, have invented an Improvement in Bobbin Take-Ups for Looms, of which the following description, in connection with the accompanying drawings, is a specification, like letters on 10 the drawings representing like parts.

Our invention relates to narrow-ware looms, particularly to looms for weaving simultaneously a plurality of strips, ribbons, or tapes for any of the various uses for which 15 such strips or fabrics are adapted. In looms of this type as heretofore constructed difficulty has invariably been encountered in providing a proper take-up for the several woven strips of fabric, it having been found 20 that ordinary take-up mechanisms, such as used in the weaving of wide fabrics, are wholly unadapted for narrow-ware looms. Prior to our invention the common practice has been to lead such strips or tapes from 25 the feed or take-up roller into boxes, where they quickly accumulate, requiring the loom to be stopped and the strips removed before the loom can continue to operate.

Attempts have been made to wind the 30 woven strips upon bobbins or spools frictionally mounted upon a rotating shaft; but this means has proven unsuccessful, because of inability properly to control the rotative speed of the bobbins. Furthermore, where 35 the strips are wound with the successive convolutions overlying one upon another, or where there is a very short lateral traverse, the bobbins are found to build up so rapidly as to require frequent stopping of the loom 40 for the insertion of new bobbins.

Our invention aims to eliminate these difficulties by providing bobbin take-up means having the capacity to receive any desired length of the woven fabric, thus permitting 45 the loom to be run uninterruptedly, excepting, of course, stopping for breakage of filling, whereby the greatest possible output of the loom is obtained. Our invention also leaves the woven strips in such form as to permit of

their being "cut" whenever desired and 50 stored or handled without danger of collapsing the bobbin.

The various features of our invention will be best understood from a description of one embodiment thereof shown in the accompanying drawings, wherein—

Figure 1, in front elevation, shows an end portion of a narrow-ware or ribbon loom of ordinary construction equipped with devices for carrying out our invention; Fig. 2, a rear elevation of the parts shown in Fig. 1; Fig. 3, a cross-section taken on the dotted line 3-3, Fig. 1; Fig. 4, a detail showing the gearing for rotating the bobbin-driving cylinder and traverse-cam; Figs. 5, 6, and 7, details, 65 respectively, of one of the traverse-fingers.

Referring first to Figs. 1 to 3, inclusive, the frame A, breast-beam a, lay B, with its reeds b and usual narrow-ware shuttles b', said lay being driven from the crank-shaft 70 b², the harness-frames C, suitably connected with the harness-lever c, with driving mechanism therefor, are and may be of usual type or construction so far as our invention is concerned. Below the breast-beam a is the 75 usual feed-roller d, the same being journaled at its ends in the frame and positively driven by any of the usual feed-roller-driving mechanisms typified at D, Fig. 1. This feed-roller, as here shown, is provided with 80 a friction-surface d—such, for instance, as sandpaper—and upon this friction-surface rest a plurality of felt-covered rollers d², equal in number to the number of strips of fabric capable of being simultaneously woven 85 upon the loom, said rollers d² being mounted in the free ends of the swinging carriers d³, depending from the breast-beam.

In the present embodiment of our invention the bobbins are driven by a cylinder 90 which is independent of the cylinder or roller d, said bobbin-driving cylinder being here indicated at E. This cylinder may be located at the rear or at the front of the loom, as convenience dictates, the same being herein 95 shown at the rear of the loom. This bobbin-driving cylinder may be driven in suitable manner, as by the sprocket-chain e, from the

feed roller or cylinder d or shaft thereof, the said cylinders or rollers E and d thus having the same rotative speed.

The bobbin-driving cylinder preferably has a friction-surface, such as sandpaper, and upon this surface rest the peripheries of the bobbins F which are being wound or formed. These bobbins are wound upon any suitable cores f , journaled in the free arms f' of the carriers f' , fulcrumed at f^2 .

Above the bobbins is arranged a traverse-shaft h , mounted to slide endwise in suitable bearings in the frame and provided along its length with a plurality of traverse-fingers h' , one for each bobbin to be wound.

Referring to Figs. 2 and 4, the traverse-shaft at one end of the loom is provided with a roller-stud h^2 , which engages the traverse-cam h^3 . (Shown as loosely mounted upon a stud h^4 .) The hub of this cam (see Fig. 4) is provided with a gear h^5 , driven through an intermediate gear h^6 from and by a pinion h^7 , fast on the shaft of the bobbin-driving cylinder E , so that the rotative speed of the traverse-cam and the traverse movements of the traverse-fingers bear always a fixed relation to the rotation of the bobbin-driving cylinder E .

Referring now to Fig. 3, the warps w from a suitable source (not shown) are conducted in usual manner to and through the harness-frames and the reed on the lay, and in the movements of the latter and the shuttles carried thereby the weft-threads are interwoven therewith at the fell w' , the completed or woven strips or ribbons being carried, for instance, about the guide-rods w^2 , thence downward to and about the feed-roller d and about the smaller tension-rollers d^2 , resting in contact therewith. The woven ribbons or tapes are then conducted, preferably, about a guide-rod w^3 , from which they pass to the traverse-fingers h' . One series of ribbons or tapes, comprising ordinarily one-half those in the loom, are shown conducted directly to the rearwardly-projected traverse-fingers, passing through slots h^8 therein to the top sides of the fingers, thence back again through other slots to the cores of the bobbins or to the bobbins upon the cores. The other series of tapes for the forwardly-projecting fingers, Fig. 3, are carried over the traverse-rod h and preferably rest in guide-notches h^9 in the upper ends of their respective traverse-fingers, passing thence behind and under the traverse-rod, thence through their respective fingers to the top sides thereof and back again to the under sides of the fingers and to the bobbin-cores or to the bobbins thereon. In this manner the several traverse-fingers are held by the tension upon their respective tapes or ribbons in operative contact with the bobbins which are being built up.

In the operation of the loom the rotative speed of the feed-roller is adjusted in usual

manner by means of its feed or driving mechanism to take up or feed the fabric at a speed that will give the desired number of picks to the inch.

Since the bobbin-driving cylinder E has the same surface speed as the feed-roller d , the surface speed of the bobbins, which rest by gravity in contact with the said cylinder E , likewise is the same as that of the said feed-roller, and this regardless of the diameters of several bobbins. In fact, some of the bobbins may be of one and others of a different diameter, yet the winding operation remains the same, since the surface speed at 80 which the winding takes place remains uniform at all times, and since the traverse-rod h is driven positively by and from the bobbin-driving cylinder E it follows that the movements of the several traverse-fingers 85 bear a constant ratio or proportion to the rotative movements of the several bobbins, whatever be the respective diameters of the latter. Consequently uniformity of winding is insured throughout the entire building up 90 of the bobbin.

The traverse-fingers h' , Figs. 5 to 7, are provided, respectively, with lugs h^9 , which embrace and are adjustable upon the traverse-rod h , and between each pair of lugs h^9 of each traverse-finger is arranged a collar h^{10} , also adjustable on the traverse-rod and having a set-screw h^{11} or other clamping means whereby the position of each collar and of each traverse-finger along the rod h may be 100 determined and adjusted at will. The surface or winding speed of the several bobbins being identical with that of the feeding-roller d , there is no variation in tension upon the fabric strips or ribbons, consequently no tendency to pull over or collapse the bobbin as the latter increases in diameter.

Our invention also provides for winding in a single bobbin sufficient length of fabric to care for an entire week's output of the loom, 110 or more if desired. While this would not be practicable were it attempted to wind the successive convolutions of the fabric one directly upon the other, our invention contemplates the laying of one convolution in advance of or behind the preceding, forming 115 relatively long bobbins, the length of traverse from one to the opposite ends whereof greatly exceeds the distance separating adjacent tapes being woven upon the looms. Thus 120 the diameters of the bobbins may be much reduced, making it possible to wind long lengths of fabric upon a single bobbin without requiring the cutting thereof.

Since the loom is fitted to weave as many 125 strips of fabric as are possible in a given length of loom, the increase of the lengths of the bobbins beyond the spacing of the fabric strips when woven requires the bobbins to be arranged to rotate about different axes instead of one and the same axis or carrying-shaft, as heretofore. In the present instance

we have provided for this by arranging the bobbins alternately at opposite sides of the vertical center of the driving-cylinder E, said bobbins being thus staggered one relative to another and overlapping each other, as it were, so that each bobbin may thus be built up of a length at least twice what would be possible were the bobbins arranged substantially in line, as heretofore.

10. The lengths of the bobbins are such that there is no liability whatever of their collapse after having been once formed. Thus they may be stored and handled with great facility.

Our invention is not limited to the particular embodiment here shown and described, for obviously the same may be varied without departing from the spirit and scope of the invention.

We claim—

20. 1. In a loom for weaving narrow fabrics the combination with weaving devices of a fabric take-up comprising a peripherally-driven bobbin and traverse means to lay the fabric spirally thereon.

25. 2. In a loom for weaving narrow fabrics, the combination with weaving devices of a take-up comprising one or more bobbins, means to rotate the same without slip at the speed of production of the fabric and traverse means 30 to lay the fabric on said bobbin or bobbins.

35. 3. In a loom for weaving narrow fabrics the combination with weaving devices for weaving simultaneously a plurality of fabric strips of take-up means comprising a plurality of peripherally-driven take-up bobbins, a common driving-cylinder with which said bobbins frictionally contact at their peripheries, and traverse means operating simultaneously in connection with said bobbins, to lay the fabric 40 strips spirally thereon.

45. 4. In a loom the combination with weaving devices of a bobbin take-up for the woven fabric, said take-up comprising a plurality of bobbins and a frictional bobbin-driving cylinder common to and for driving all said bobbins through frictional contact thereof with the fabrics comprising the said bobbins and traverse means for directing the fabric upon the several bobbins.

50. 5. In a loom the combination with weaving devices of a bobbin take-up for the woven fabric, said take-up comprising a plurality of bobbins, means to rotate the same, and traverse devices therefor having each a range of movement exceeding the spacing of adjacent strips of fabric and offset one relative to another.

60. 6. In a loom the combination with weaving devices of a bobbin take-up for the woven fabric, said take-up comprising a plurality of bobbins, traverse devices therefor having each a range of movement exceeding the spacing of adjacent strips of fabric and offset one relative to another and a single driver for 65 said bobbins.

7. In a loom the combination with weaving devices of a bobbin take-up for the woven

fabric, said take-up comprising a driving-cylinder, a plurality of series of bobbins, carriers therefor arranged to carry their respective bobbins in frictional contact with said driving-cylinder and traverse means for said bobbins.

8. In a loom the combination with weaving devices of a bobbin take-up for the woven fabric, said take-up comprising a driving-cylinder, a plurality of series of bobbin-carriers adapted for peripheral drive of their respective bobbins by said cylinder, a traverse-rod, means to operate it and traverse-fingers 80 thereon.

9. In a loom the combination with weaving devices of a bobbin take-up for the woven fabric, said take-up comprising a driving-cylinder, a plurality of series of swinging bobbin-carriers arranged at opposite sides said cylinder and extended thereover, a traverse-rod, means to operate it and traverse-fingers 85 thereon extended alternately in opposite directions.

10. In a loom the combination with weaving devices of a bobbin take-up for the woven fabric, said take-up comprising a bobbin-driving cylinder, means to rotate same at a surface speed corresponding to the feed of 95 the fabric, one or more bobbins driven by frictional contact with said cylinder of the fabric of said bobbin or bobbins and traverse means for the respective bobbins.

11. In a loom the combination with weaving devices of a bobbin take-up for the woven fabric, said take-up comprising a feed-roller to draw the fabric from the weaving devices, a bobbin-driving cylinder geared thereto, one or more bobbins arranged to be rotated by 105 frictional contact with said cylinder, and traverse mechanism.

12. In a loom the combination with weaving devices of a bobbin take-up for the woven fabric, said take-up comprising a bobbin-driving cylinder, peripherally-driven bobbins movably mounted adjacent thereto, a traverse-rod, and traverse-fingers adjustably arranged thereon.

13. In a loom the combination with weaving devices of a bobbin take-up for the woven fabric, said take-up comprising a feed-roller for the woven fabric, a bobbin-winding cylinder, one or more bobbins arranged adjacent thereto, a traverse-finger for each bobbin and 120 means to operate it, the fabric passing to the bobbin acting to hold the traverse-finger in operative relation to the bobbin.

14. In a loom the combination with weaving devices of a bobbin take-up for the woven 125 fabric, said take-up comprising a bobbin-driving cylinder, a plurality of series of bobbins arranged adjacent thereto and to be rotated therefrom, a plurality of oppositely-extended traverse-fingers, and means to operate the same, said fabric strips engaging their respective fingers in a manner tending to hold the latter in operative relation to their respective bobbins.

15. In a loom the combination with weaving devices of a bobbin take-up for the woven fabric, said take-up comprising a bobbin-driver, a peripherally-driven bobbin-carrier, 5 and a traverse-finger having a guide at its heel through which the fabric is passed to said finger and the bobbin.

16. A loom containing weaving devices and a feed cylinder or roller for the woven fabric 10 in combination with a bobbin take-up comprising one or more bobbins and means to drive the same without slip from said feed cylinder or roller at a surface speed always the same as the surface-speed of said feed 15 cylinder or roller.

17. A loom containing weaving devices and

a feed cylinder or roller for the woven fabric in combination with a bobbin take-up comprising one or more bobbins, means to drive the same without slip from said feed cylinder 20 or roller at a surface speed always the same as the surface speed of said feed cylinder or roller, and a traverse device for each bobbin.

In testimony whereof we have signed our names to this specification in the presence of 25 two subscribing witnesses.

NATHANIEL H. MERRIAM.
EDMUND H. SAWYER.
